UNITED STATES PATENT OFFICE.

OTIS H. FISK, OF CINCINNATI, OHIO.

ABRASING AND POLISHING BLOCK.

1,183,444.

Specification of Letters Patent. Patented May 16, 1916.

Application filed August 4, 1915. Serial No. 43,520.

To all whom it may concern:

Be it known that I, OTIS H. FISK, a citizen of the United States of America, and resident of Cincinnati, county of Hamilton, 5 and State of Ohio, have invented certain new and useful Improvements in Abrasing and Polishing Blocks, of which the following is a specification.

The object of my invention is to produce 10 an abrasing and polishing block for holding strips of sand paper, emery cloth, or polishing cloth, which is more compact and cheaper than other polishing blocks known to me.

15 This and other objects are attained in the polishing block described in the following specification, and illustrated in the accompanying drawings, in which,

20 Figure 1 is a plan view of the abrasing and polishing block embodying my invention. Fig. 2 is a sectional view taken on the line 2—2 of Fig. 1.

The abrasing and polishing block embodying my invention comprises a base 3, 25 adapted to support a strip of abrasive or polishing material, and a clamp 4 mounted on the upper side of the base and adapted to clamp the opposite ends of the strip of abrasive or polishing material, between the 30 inner edges 5 and 6 of lugs 7 and 8, at the ends of the base 3, and the outer edges 9 and 10 of the clamps. The coöperating edges of the base and clamp are inclined 35 downwardly toward the ends of the base, for the purpose of drawing the abrasive or 40 polishing strip more tightly over the supporting surface of the base, as well as to draw and maintain the clamp in close engagement with the upper surface of the 45 base. Adjacent to each end of the base and immediately beneath the overhanging inclined edges of the lugs 7 and 8, grooves 50 11 and 12 are formed in the upper face of the base 3. These grooves are provided 55 for receiving the ends of the strip mounted on the base, should they be so long as to extend beyond the lower ends of the inclined edges of the lugs.

The clamp consists of two portions 13 50 and 14, between which are located pins 15 and 16 and springs 17 and 18, the pins being securely mounted in one of the blocks and extending from the inner edge thereof, and into bores 19 and 20 in the inner edge 55 of the opposite portion of the clamp. Portions of the bores 19 and 20 are enlarged,

and portions 21 and 22 of the bores in which the pins are securely mounted preferably are also enlarged, for the purpose of receiving the ends of the springs which are 60 mounted on the pins. The pins are made of a length sufficient to extend considerably into both portions of the clamp, for the purpose of maintaining perfect alinement of the portions, and of preventing their buckling when mounted in place on the base. 65

In my improved abrasing and polishing block, I have produced a cheap, strong, compact and efficient construction, in which the base and clamp portions may be made either 70 of wood or metal, or other material, wood being preferred, because of its cheapness. In case wood is employed, the pins may consist of nails driven into one portion of the clamp and extending into the other portion 75 of the clamp, with the springs mounted on the nails and extending into the bores in the manner shown.

In securing the abrasing or polishing strip in place, the inner edges of the clamp are 80 brought in contact with the outer edges of the lugs and are then forced inward, thus carrying the abrasing or polishing material securely into place and drawing it tight across the outer surface of the base. This 85 clamping action not only holds the abrasing or polishing material tight across the base, but prevents its having any transverse motion relatively to the base.

If desirable, a cushioning material K, such 90 as felt, may be placed between the outer surface of the base and the abrasing or polishing material.

Having thus described my invention, what I claim is:

1. An abrasing and polishing block comprising a base, and a clamp mounted on the base, said base having upwardly extending ends with dove-tail inner edges, said clamp having its outer edges inclined to coöperate 100 with the dove-tail edges of the base and consisting of two portions, pins reciprocally connecting the portions, and springs mounted on the pins adapted to normally force the portions apart to bring the inclined and 105 dove-tail edges of the clamp and base into clamping engagement.

2. In an abrasing and polishing block, the combination of a base having upwardly extending ends with grooves located adjacent to the ends, said ends having their inner edges downwardly and outwardly in- 110

clined, whereby a transversely extending dove-tail slot is formed on the base, and a clamp consisting of two portions, mounted in the slot, each of said portions have one of its edges outwardly and downwardly inclined to coöperate with one of the inclined inner edges of the ends, and means for maintaining the portions in alinement and the inclined edges of the base and portions in clamping engagement with the ends of the base.

3. In combination in an abrasing and polishing block, a base having upwardly extending ends with grooves located adjacent to the ends adapted to receive the ends of a piece of abrading or polishing material stretched across the base, said ends having their inner edges downwardly and outwardly inclined whereby a transversely ex-

tending dove-tail slot is formed on the base, and a clamp consisting of two portions, mounted in the slot, each of said portions having one of its edges outwardly and downwardly inclined to coöperate with one of the inclined inner edges of the ends, pins 25 reciprocally connecting the portions, and springs mounted on the pins, adapted to normally force the portions apart to maintain the inclined edges of the ends of the base and clamp in clamping engagement. 30

In testimony whereof, I have hereunto subscribed my name this 27th day of July, 1915.

OTIS H. FISK.
